CLAIM

The ornamental design for a LED display module for a gaming display as shown and described.

DESCRIPTION

FIG. 1 is a perspective view of an LED display module shown with environment and in accordance with the new design.

FIG. 2 is a perspective view of the LED display module shown in FIG. 1.

FIG. 3 is a top view thereof.

FIG. 4 is a front view thereof.

FIG. 5 is a side view thereof; and,

FIG. 6 is a rear view thereof.

The ornamental design which is claimed is shown in solid lines in the drawings. Stippling in the drawings is used to indicate a contrast in appearance between an LED display surface of the LED display module and other surfaces of the LED display module, with no specific color or feature being claimed. The broken lines depict portions of the article and environment that form no part of the claimed design.
